HAND PUMP

Gordon Allard, Menomonee Falls, Wis., assignor to
Applied Power Industries, Inc., a corporation of Wis-
consin

Filed July 27, 1965, Ser. No. 86,311

Term of patent 14 years

(Cl. D65—1)

Fig. 1.

Fig. 4.

Fig. 3.

Fig. 2.

FIGURE 1 is a top, side and end perspective view of a hand pump embodying my new design;

FIGURE 2 is an elevational view of the hand pump taken from the other side thereof;

FIGURE 3 is a top view thereof; and

FIGURE 4 is a view of the hand pump taken from the other end thereof.

The base mounting plate, reservoir, actuating handle and release valve knob are all shown in broken lines for illustrative purposes only.

The actuating handle is shown broken away in FIG. 1 and is shown fragmentarily in FIGS. 2 and 3 for convenience of illustration.

I claim:

The ornamental design for a hand pump, substantially as shown and described.
